UNITED STATES PATENT OFFICE.

GEORGE A. E. JONES, OF NEW LONDON, CONNECTICUT, ASSIGNOR OF ONE-THIRD TO ALBERT B. HART AND ONE-THIRD TO HAROLD H. STARR, BOTH OF NEW LONDON, CONNECTICUT.

AUTOMATIC FEED RIVET HEATER.

Application filed May 20, 1921. Serial No. 471,283.

My invention relates to a new and improved method of, and apparatus for, use in metal working operations, in which, low voltage, high amperage electric currents are passed through the work, such as bolts, rivets or other like articles or stock, and through the inherent resistances of such bolts, etc., raise them to the desired working plasticity for forming, forging rivet-heading in situ etc., or other desired manipulation at high temperatures, and the same is an improvement upon my co-pending application for Letters Patent of the United States, Serial No. 431,999, filed December 20, 1920, and as in such filed application, in so far as it concerns the apparatus, although not limited to such use, relates more particularly to electric-forges, or similar apparatus for passing an electric current of high amperage and heating quality, through the rivets, or other stock, for making the same plastic for permanently rivet-heading the same in position, in boilers, buildings, bridges, etc.

Broadly, the objects of my invention as to the apparatus which I have devised for carrying out my said method, are to provide an automatic apparatus, preferably and usually portable, being mounted on wheels, or casters, as shown in Fig. 6, by the use of which, a greater number of rivets can, by my new method, be heated in a given time, and automatically ejected therefrom when at the right heat; which I consider to be the very crux and salient point of my invention, or inventions, as hereinafter more particularly pointed out in the claims thus bringing about greater and quicker heating of rivets, etc. than has ever hitherto been known, and this at less cost.

To such ends, my said improved electric heating apparatus comprises a movable carrier, usually, but not necessarily of the revoluble carrier-plate form shown, and described herein, or any desired plural number of such carrier-plates (or any other suitable form of moving carrier) such carrier-plate or plates being provided with a plurality of stock-carrying slots open at one end, for the ejection of the stock when heated, which bolt-carrying slots, in the circular form of carrier-plate shown and described herein are usually and preferably eight in

number, as shown; the four outer slots opening outward at the periphery, and the four like inner slots opening inward, into the orifices of the central open spider-hub portion of such carrier-plate; a guiding-member for each of such carrier-plates for preventing the rivets when once inserted in such carrier-slots, from passing out of said slots until they are automatically gravitationally discharged from the open ends thereof after having been heated to the necessary temperature, for the working required by the automatic action of the guiding-member; mechanism for intermittently rotating the carrier-plate or plates with a dwell between each movement; a heating electrode or plurality of electrodes beneath each carrier-plate; means for positionally vertically adjusting the electrodes for rivets of different lengths; an electric supply usually but not necessarily a transformer, for producing a direct or intermittent straight heating current of the required high-amperage; derived from a suitable alternating current supply; an electro-conductive bridge-member situated above each of the carrier-plates, against which, the head or upper end portion of the rivets or other articles will be forced into contact, upon the raising upward into contacting position of the movable lower electrodes, in such manner that the heating-current will usually, but not necessarily in all cases, pass in series through one rivet, then the bridge-member, then the other rivet carried by the same carrier-plate and complete the heating circuit; means or mechanism for intermittently raising and lowering the lower reciprocating electrode or electrodes, with a dwell between such movements sufficient to bring the rivet to the proper heat for working; and a constantly rotating prime-mover usually an electric motor, actuating such moving mechanism, the times of the rotation and the heating dwell being controlled by varying the speed of the prime-mover.

Such apparatus is of a simple and cheap form of construction, easily operated, highly efficient and of long life. Other objects of the invention will appear as the description proceeds; and while herein minute details of the invention are described, my said invention is not limited to the exact construc-

tions, combinations or positioning of the various elements thereof shown; as many changes may be made therein, both in construction, combination and arrangement, without in any manner departing from the scope of my invention, which is fully shown and described in the following specification, of which the accompanying drawings form a part, wherein similar letters or numerals 10 of reference designate like or equivalent parts wherever found through the several views, and in which:

Figure 1 is a front perspective view in elevation of my said improved electric heating 15 device for heating rivets, etc.

Fig. 2 is a view in detail on an enlarged scale, looking from the top of Fig. 1 of the mechanism for intermittently rotating each of the rotating carrier-plates by a step by 20 step movement, with a heating dwell between the movements.

Fig. 3 is a like front detail view of a portion of the mechanism shown in Figs. 1, 2 25 and 4, taken in section on the line 3—3 of Fig. 4, showing the left-hand carrier-plate, with its two lower electrodes in the lower and depressed and rivet-releasing position; and in dotted lines showing the two already heated rivets released and gravitationally 30 falling from the carrier-plate, into any suitable receptacle, not shown.

Fig. 4 is a top-plan of the device.

Fig. 5 is a top-plan view of the two curved 35 guide members situated immediately below the two carrier-plates looking downward as to Fig. 1, and from below, looking upward in Fig. 1.

Fig. 6 is a side view in perspective and elevation, partially in section, of the complete 40 device looking toward the left of Figs. 1 and 4 in the direction of the arrows.

Fig. 7 is a top-plan detail view of a portion of a modified form of carrier-plate, showing means for varying the width of the 45 slots to adapt the same for use in holding rivets of different diameters.

Fig. 8 is a diagrammatic view of the 50 bridging-electro-contact members, movable-electrodes, transformers, primary current generator, electric wiring, prime-mover motor, etc., in a machine of the two carrier-plate form of construction shown herein, with rivets in process of heating; and

Fig. 9 is a front exterior view in elevation 55 on a reduced scale, of the particular type of variable transformer, which I prefer to use in such device, as shown in the diagrammatic view, Fig. 8.

As shown in the drawing:—

The main frame supporting portion of my 60 said electric rivet heating apparatus consists of a main-frame F, in this particular case usually and preferably built up of four upright rolled steel corner members 1, usually of L-angle-bar shape in cross-

section; like steel top side bar-members 2; intermediate members 2', and 2''; and front intermediate members 3 and 3'; the bottom member 3'', and top and bottom horizontal like members 4 and 5, which are usually of 70 the forms in cross section indicated, some being flat plates, and others of substantially L-shaped form in cross-section as shown.

At or adjacent to the center of such main frame, extending across, and rigidly secured 75 at either end to the intermediate side pieces or members 2', are two channel-bars indicated by the letters U and U', and supporting the motor M, which is rigidly secured thereto by bolts 5.

As shown in Fig. 1, the front bar 3 is provided adjacent to either end with two outer vertical journal boxes 4', in which are rotatively mounted the shafts 22, 22', upon the upper ends of which are rigidly secured the 80 rivet carrier-plates C, C', between which are four like journal-boxes 7; in each of which are rotatively and reciprocatingly mounted the vertical upper portions 8 of the lower vertically movable electrode shafts 9; the lower portions 10 of which are connected with the upper portion 8 by a turn-buckle 9 by the manipulation of which each of the said electrode-shafts may be lengthened or shortened, to operate upon bolts, rivets, etc., 85 of various lengths; and such turn-buckle shafts are supported at the lower ends in step journal-boxes 11, so as to be revoluble and vertically reciprocatable therein.

And secured within the L-shaped upright 90 corner-members 1 of the frame are horizontal journal-boxes 12 (Fig. 1) in which are revolvably mounted the journals of the cam-shaft 13, having mounted thereon a worm-screw gear-wheel 14, actuated by the worm-screw gear 15 mounted upon the shaft 16, carrying a spur gear-wheel 17, meshing with the smaller spur gear-pinion 18, mounted upon the shaft 19, of the prime mover or motor M.

Rigidly secured to the cam-shafts 13 in vertical line with the two outer upper and lower journal-boxes 6 and 11', is a mutilated spiral gear-wheel or cam-member 20 having a hub 20' secured in any desired position by 105 a set screw 20" provided with a short single mutilated spiral screw member 21; and meshing therewith and mounted rigidly upon the supporting operating shaft 22 or 22' as the case may be, carrying at their upper ends respectively, the revoluble rivet magazines or stock carrier-plates C and C', constituting a rotatable work holding means. 110 is the coacting four-toothed spiral gear-wheel 23 having the four spiral teeth or screw-threads 23, and by this arrangement it will be seen that upon the rotation of the cam shaft 13, each of said carrier-plate shafts 22 and 22' will be simultaneously rotated intermittently four times to each single 115 120 125 130

rotation of the cam shaft 13, with a dwell between each of such movements, of sufficient time to heat the two rivets at the time included in the high amperage electric heating-circuit or circuits, to the exact plastic working temperature required; and no more; whereby over-heating, burning, scale formation etc., of such rivets is absolutely prevented.

10 And it will be also seen that if one of the members 20 has its tooth 21 at the forward side, while the other has its like member at the rear, while one carrier-plate is in the dwell, the other is in rotative feeding motion, while if both are in like position, as 15 both teeth 21 to the front and rear both are simultaneously in heat or dwell.

Located immediately below the cam-shaft 13, and secured rigidly upon the lower portion 10 of each of the turn-buckle shafts, is a peripherally slotted collar 35. And formed integral with, or rigidly secured to, the front portion of the channel-bar U, which together with the like shorter L-shaped channel-bar 25, Fig. 4, supports the prime-mover or motor M, are the upwardly extending bracket-members 31, and 31', pivotally secured within which by the pivot nut-bolts 32, and 32', are the rear ends of the electrode depressing levers 33, (Figs. 4 and 6); such levers 33 and 33' each carrying at their forward ends, (as shown in Figs. 1, 4 and 6) the double electrode-shaft depressing forks 34'; the inwardly extending pins 27, of 30 which extend inward into the peripheral slot 27', of the adjacent registering lift-collar 25, rigidly secured to the electrode turn-buckle shaft 10; between which collars 25, and the lower journal boxes 11, in which 40 such turn-buckle shafts are vertically and reciprocally mounted, are interposed coil-springs 35', which normally force such two-twin electrodes 30 and 30' simultaneously upward, against the lower ends of the two-rivets in the particular carrier-plate immediately above such electrodes 30 or 30', at 45 the moment, so as to bring the heads of such rivets into contact with the lower surface of the electro-conductive bridge-member B or 50 B', accordingly as such rivets are carried by the carrier-plate C or C'.

Rigidly secured upon the cam shaft 13, one between the two turn-buckle shafts 10 of the twin-carrying electrodes 30; and the 55 other in the same position between the like shafts supporting the electrodes 30', are two cams 36 and 36' respectively, the peripheral surfaces of which are in constant contact with a friction roller 37, rotating upon a 60 stud-pin mounted upon a shaft 38, the ends which are supported in the opposing faces of the double fork of the lever 33, or 33', as the case may be, (Fig. 4) and it will be seen that when the depressing outer larger diametered peripheral portion 39, of such cam

is brought into contact with and passes over the friction-roller 37, carried by the depressing lever 33, 33', as the case may be, (Fig. 6) such lever will be forced downward in such manner as to depress such 70 double forked-lever, so as to carry simultaneously downward the two twin turn-buckle shafts, with which 37 is connected into the rivet releasing-position shown in Fig. 3; but that when the lesser diametered portion 39' (Fig. 6), of such cam 36, or 36', is in contact with 37, (Fig. 6); that the resiliency of the coil springs 35, by their action upon the collars 25, will force the turn-buckle shafts and the twin electrodes 30, or 30', carried thereon upward in such manner as to lift the registering rivets or other stock in the carrier-slots into contact with the conductive bridge-member immediately above; thus closing the heating circuit thru such registering rivets. And the path of the current is usually of what is known as tandem-series, flowing first from the plus pole moving-electrode through the rivet to the conductive bridge-member, from the bridge-member through the other rivet, to the other twin moving-electrode, thence to the minus pole of the electric heating supply, all as shown in diagram in Fig. 8, by the arrows and plus and minus signs. 80

And it is also evident that by having the conductive bridge-member, or members, connected to, say the minus pole of the heating current supply, or vice versa, as by 42', in dotted lines, Fig. 6, while the two coacting 90 movable electrodes are connected with the opposite or plus pole, or vice versa, as shown at 42' in dotted lines, two rivets, etc., can be heated in like manner, without being connected in tandem-series; the path of the heating current being of the type of what 95 is known as in parallel series.

That is, from each of the twin plus poles (or vice versa) of each of the electrodes 30, or 30', the plus-current passes through its individual rivet or stock-piece to the particular conductive-bridge-member situated above such electrode, and thence to the minus pole of the electric heating current supply. And it will be seen that by using 100 this conductive circuit in parallel series, and by making the carrier whether of the rotating form shown, or of any other suitable moving form, which will carry and bring simultaneously into position between the plus and minus electrodes, a plurality of rivets or other stock, that a single rivet or stock piece, or an almost innumerable number of such rivets, etc., may be heated 110 and delivered simultaneously.

120 And it is evident, although I have not deemed it essential to show the same in the drawing herein, that the circular carrier-plate in the form here shown could easily be made with a second, or any desired num- 130

ber of spiders, having delivery orifices connected with rivet holding slots, such spider or spiders being situated concentrically exterior to the single central-spider shown in Figs. 1 and 3, whereby three or more rivets could be heated and delivered simultaneously. And it is also evident that with the parallel series type of heating current a single bridge-member, could be used for the lower movable as well as the upper immovable bridge-member or electrode.

It will also be seen that the particular form of construction shown in the drawings, will be especially valuable for general contractors, where there is frequently need for simultaneous delivery of several rivets of different diameters, consequently needing variation of the diameters of the carrying-slots; and also different amperages of heating current; and it is also evident that by the use of my said machine with two carrier-plates with adjustable rivet slots, and like electrodes, each carried by an adjustable and reciprocating turn-buckle shaft, when coupled with the universally variable single primary coil, and double variable secondary coil transformer as shown, as many as four rivets or pieces of the same size stock, or of different diameters and lengths, may be electrically heated and delivered simultaneously or only a single rivet can be heated and delivered.

While two transformers serving both sets of electrodes 30 and 30' each of which transformers is variable as to its primary, but not as to its secondary, may be used, the cost of installation, space, weight and cost of current used are each reduced to a minimum by the use of the particular type of universally variable transformer shown in Figs. 8 and 9; wherein the transformer inducing magnetic-member is of the form shown in Fig. 9, with two exterior and one interior member in a closed magnetic circuit. In such device the primary coil 40 is concentrically mounted upon the central leg of the magnetic member, while the secondary coils A and B, flanking the same on opposite sides are each mounted upon one of the side legs of such magnetic member. And as in this type of transformer already in use and on the market, both primary and secondary currents for each two electrodes 30 and 30', may be separately widely varied, by the use of only one transformer, the heating current passing through the electrode conductive bridge-member B or B', may each be made to deliver currents of different voltages, or amperages, or both, as may be required, merely by setting the primary-coil switch member D, in such position that it will give the required greatest heating current to one set of electrodes, and at the same time give the requisite lesser heating cur-

rent to the other bridge-member, by setting the secondary cut-out switches O and O', to different positions. In the diagram Fig. 8, it will be seen that the transformer secondary coil A, inasmuch as its switch cut-out member O is in position to put in circuit only one-half of the coils therein, while the secondary coil B has its like switch cut-out member O', in position to put in circuit all the coils of B, that at any given time the secondary coil B, whatever the voltage at the moment passing through the primary central A. C. current coil K (which may be widely varied by proper positioning of the cut-out switch-member O (Fig. 6) of such single primary coil K, Figs. 8 and 9,) that the amperage delivered by the secondary coil A, when its circuit is closed through the bringing of the rivet-heads into contact with the electro-conductive bridge-member B', will be of just one-half the amperage, and consequently of just one-half the rivet-heating power, of the current delivered by the secondary coil B.

Suitable connections, and a controlling rheostat, and switch, are of course provided for the prime-mover motor M, but they being of well known form I have not deemed it essential to show the same in the drawings. Nor have I deemed it necessary to show (Fig. 6) more than the hand-levers on the switch-board of the primary, and two secondary coils of the universally variable transformer T, such hand-levers being each positioned to accord with the circuits as shown in diagram in Fig. 8.

The electrodes 30 and 30', are preferably formed of cold-rolled electrolytic pure copper; and are made of sufficient mass as not to be highly heated throughout by the passage of the current. Each pair of movable electrodes 30 and 30', are each separately mounted on top of one of the turn-buckle vertically reciprocating shafts 9; are insulated from such shaft by an insulating block 40; and are connected one with the plus, and the other with the minus pole of one of the secondary coils of the transformer by flexible resilient conductive ribbon-strips 41 and 41', usually of copper, brass, etc., while the electro-conductive bridge members B and B' are supported by like thicker, less resilient supporting bars 42 (Fig. 6) bolted to the frame, so as to be practically immovable, and are insulated from the supporting bars 42, by insulation 43; in such manner that when either pair of the reciprocating turn-buckle shafts supporting the electrodes 30, or 30', are raised up by the action of the springs 35, the two rivets at the moment situated underneath such electro-conductive bridge member B or B', will have the heads thereof brought into contact with such superposed bridge-member, so as to make a

closed heating-circuit in series thru each pair of rivets by way of such bridge-member, all as clearly indicated in the diagram Fig. 8.

Mounted upon the intermittently rotated 5 carrier-shafts 22 and 22' are the carrier-plates C and C', constituting the rivet holding magazines, which are usually and preferably of the circular central open spider-like form shown. While the number of 10 rivet-carrying slots of such carrier or support shown in the drawing total eight in number; four upon the periphery with the open ends outward; and four at the periphery of the central-spider, with open ends 15 delivering the heated rivets inward to the interstices or orifices of the four-spoked central spider, it is of course evident that the number of such slots may be increased or diminished without in any manner departing from 20 the scope of my invention.

Secured at either end to the front corner standards of the main-frame is an L-bar 44 located and preferably immediately below and adjacent to the rearward edges of the 25 rotating carrier-plates C and C'; and secured to such bar 44 usually by a screw or screws 44' is a rivet guide member G usually and preferably of the single integral-piece double inner and outer volute whorl coil form 30 and shape shown in detail in the top-plan view thereof, Fig. 5. And it will be seen (Figs. 3, 4 and 5) that when the rivets are dropped by hand into the carrier-plate 46, when they are in the extreme forward feeding 35 position indicated at 46', Figs. 1, 4 and 5, their lower ends will project slightly below the guide member G with the outer side of the rivets in the outer feed slots in contact with the inner concave face of the outer 40 whorl or volute of the guide member G, and with the inner side of the rivets in the inner spider-slots in contact with the outer convex side of the inner smaller diametered whorl or volute of such guide member G, 45 so that they will be retained in such open ended slots as the carrier-plates are rotated as indicated by the arrows in Figs. 4 and 5, as the carrier shafts 22 and 22' are intermittently rotated step by step the left hand 50 one 22, clock-wise, and the right hand one 22' anti-clock-wise, as indicated by the arrows in Figs. 4 and 5, until they register with and are located between either the electro-conductive bridge member B or B', and 55 the electrodes 30 or 30', as the case may be; being positioned as shown in dotted lines in Figs. 4 and 5, as indicated at H; and as soon as the two rivets are so placed the circuit is closed by the automatic lifting up of 60 the electrodes as shown in Fig. 1, so as to bring the headed upper ends of the rivets into contact with the bridge member B or B', as the case may be. Thus it will be seen that the work holding magazines C and C' 65 are timed to advance at intervals relative to

the reciprocation of the electrodes 30 and 30' so that the rivets supported in such magazines will be advanced by such magazines C and C' into heating position between the electrodes B and 30, 30, or B' and 30', 30', 70 and after heating, again advance by said magazines out of heating position. In from five to six seconds of electric contact, the rivet or rivets in circuit will have reached working heat, and as soon as the carrier-plate begins its next succeeding intermittent step movement, the hot rivets will both be brought into contact with the closed looped portion of the guide member G, as shown at 47, and 47', of Fig. 5; and as the carrier-plate continues to revolve 47 will be forced along the outer peripheral carrier-slot, and 47' along the inner spider-slot and when in the position indicated by crosses surrounded by dotted lines 47¹ and 47², being wholly out of their respective slots, they will fall together by gravity into any suitable receptacle (not shown) situated in proper position beneath, the hot rivets, being ejected, and in the act of dropping being 90 indicated in the dotted lines in Figs. 3 and 5, the outer rivet by 47¹ and the inner by 47².

By my said new and improved method, and by the use of my said new and improved automatic rivet heating machine and apparatus heretofore described, rivets of $\frac{3}{4}'' \times 3\frac{1}{2}''$ length can be delivered at the proper heat for hand-riveting at the rate of ten per minute; and for bull riveting at the rate of twelve per minute, as I have proven 100 by actual operation of such machine or apparatus.

While I have shown herein two intermittently rotating peripherally and interiorly spider-like, slotted carrier-plates, each heating two rivets at a time as the two carrier-plates are intermittently rotated step by step with a sufficient dwell between such movements to bring the rivets to the proper working heat, I do not intend to limit myself to the exact form of carrier or other parts thereof shown and described herein; but, believing that I am the first person to conceive of and practically embody and put into actual working use such an automatic 105 electric heating device, I claim as my invention, both as to method and apparatus, the broad principle of a moving carrier for rivets, etc., as shown in the machine herein described, whereby and wherein a plurality 110 of rivets or other stock, without human assistance, save for the feeding of the rivets to such carrier, are automatically and intermittently singly, or in any desired plurality, brought into position, and in contact with a 115 suitable electrode or electrodes with a sufficient dwell, while included in the closed electric heating circuit, to bring such rivets or other stock to be treated to proper plasticity 120 by an electric heating current, which rivets 125

or stock as soon as heated to the proper point, will be automatically ejected from such carrier into a suitable receptacle irrespective of the particular form shown herein, as I consider any method or apparatus performing the same functions in substantially the same way as the method and machine herein described and claimed, to be clearly within the scope and purview of the 5 broad claims hereof, wherefore I consider that in its broad scope my invention or inventions cover and include, any method or machine of the broadest class or kind described, including any and all forms of moving carriers, which will carry a plurality of rivets or other like articles, and which will automatically, singly in sequence, or in any desired plural number in sequence, in like manner, bring them into position to close the 10 electric heating circuit through such rivets, heat them and thereafter automatically eject them from the machine or apparatus, and then simultaneously and automatically bring another fresh rivet or rivets into position to 15 be heated to be within the broad scope and purview of my invention or inventions as set forth in the claims hereof.

Neither do I intend in the broad claims hereof, to limit myself to any particular 20 number of such carriers or carrier-plates, nor to any particular construction, combination or arrangement of the various parts making up and comprising my said new and improved automatic rivet heating machine 25 and apparatus herein shown; and it is evident that many various changes in the construction, or of the combination and arrangement of the various elements and parts making up and comprising said apparatus, 30 may be made by any skilled mechanician, without in any manner departing from the broad scope of my invention.

It is highly essential, especially for use 35 by the general contractors in such arts as the erection of structural steel buildings, bridges, etc., that some means should be provided for quickly and easily varying the width of the rivet-carrying slots 46 for use in heating rivets of widely variant diameters; and to this end I have devised the 40 adjustable mechanism shown in detail in Fig. 7 which comprises a slot varying plate 50 contoured at the inner side 51 to the outer edge of the inner slot and contoured at its 45 outer edge at 51' to the inner edge of the outer slot coincident in axial line with such inner slot. Such slot varying plate 50, for the sake of lightness and cheapness, is drop forged or otherwise formed from thin 50 sheet-steel or other suitable metal, and is preferably provided with the inner and the outer depending flanges 51² and 51³, shown in dotted lines in Fig. 7, which extended down into the inner or outer rivet carrying 55 slots sufficiently far to hold the rivets up-

right in the slot whatever their diameter, such flanges being preferably integral, and at their junction point fitting into a suitable shaped top-cavity 56 formed in the upper face of the carrier-plate. This plate 50, for 60 purposes of adjustment is provided with a longitudinal semi-circular or segmental adjusting-slot 52 struck from the axial center 52' of the spider carrier-plate in which are located one or more (preferably two as 65 shown in Fig. 7) securing screw-bolts 53 and 54 preferably with driver slotted heads, screwing into the carrier-plate. As shown 70 in Fig. 7, the plate 50 is in its extreme right hand position with the rivet-plate rearmost, and it will be seen that when shifted backward toward the left of such Fig. 7, until the securing screw 53 is at the extreme right hand end of the slot 52, indicated by 53', this will widen both the outer peripheral 75 and the inner spider rivet heating-slots in the same degree to the full diameter possible, or to any minute graduations in between.

Inasmuch as in some cases it may be desired to have rivets or stock of different diameters carried in the inner and outer immediately adjacent carrier-slots; in such case the plate 50 is usually separated into two parts along the curved line a—a of Fig. 7, passing through the center of the adjusting-slot 52, and in such case, by using securing screws 53 and 54, with heads of considerable diameter, both plates whatever 80 their position, may be held securely in place without danger of accidental displacement, as but little strain is ever brought thereon; or each half of such plate may be provided with a separate curved slot 52, as may be desired.

In some cases, and for certain purposes, it may be extremely desirable that rivets or other stock of different diameters, or lengths, and consequently (as electric resistance is dependent upon mass) requiring currents of different amperages to bring them to just the required state of working plasticity without danger of over-heating. And it will be seen that two or more stock pieces, requiring heating currents of different amperages, though carried by the same carrier-plate, may be simultaneously heated and delivered by eliminating the electro-conductive bridge member by dividing it into two separate electrodes, a and b, as indicated by the dotted lines 60, 60' on the bridge-member B' of the diagram of Fig. 8 and connecting each separately in circuit with one pole of one of the secondary coils of the type of universally variable transformer shown in such Fig. 8, and connecting in like manner each of the coating electrodes 30' with the opposite poles of the same two separate and distinct variable secondary coils of the same 100 transformer. But in such case, if each of 105 110 115 120 125 130

the two carrier-plates is to carry say, two rivets or other stock-pieces, each requiring a current of a different amperage, in that case, the transformer T, while having but 5 one variable primary coil, has one variable secondary coil for each different amperage current required. And it will be seen that with a transformer of the universally variable type shown, that in a rotary stock-carrier machine of the type shown, having two rotary carrier-plates each simultaneously heating two rivets etc., and having my two part slot-adjusting plates 50 combined with a universal primary and secondary trans- 10 former having one central magnetic core leg, carrying the variable primary coil and four exterior magnetic core legs, each carrying a variable secondary coil, that four rivets or other stock, each of a different 15 mass, and consequently different electric conductivity requiring four currents each of different amperage, to bring them generally to proper working plastic heat may be simultaneously delivered, in proper working plastic 20 condition.

And by this arrangement, it will be seen that rivets of widely varying diameters and lengths may be at the same or different times, heated in such apparatus or machines 25 by varying the heating current supplied to the electrodes of each carrier by using the particular form of universal variable transformer hereinbefore described, and the other hereinbefore enumerated mechanism; 30 and this also, without the slightest danger of over-heating; and consequently deterioration of such rivets or stock by burning, scalding etc. But while such curved slotted double adjusting plate shown is the device 35 for varying the width of the rivet carrying slots, which I preferably use, it is evident that other devices may be used for such purposes in place thereof, and in the broad claims hereof relating thereto, I do not intend to in any manner limit myself to such 40 form of plate; but intend to cover and include in such broad claims designated thereto, any device for so varying the width of rivet or stock carrying-slots, in a movable 45 carrier of any form, in any form of electric stock heating machines.

By the words rivet or rivets, article or articles, stock or stock-pieces, when used in the description or claims hereof, I intend 50 to cover and include not alone headed rivets or bolts etc., but also unheaded, or any other work or bodies, such as small articles or pieces of stock, to which the broad principle of my said method, and my said automatic heating apparatus may be adapted and used, for any purpose, such as stamping, swaging, forging, or in any other manner changing the shape thereof, while in a plastic heated condition, as my said apparatus may 55 with immaterial changes therein be made

adaptable to an almost innumerable number of such uses with stock or articles desired to be contoured to any shape, without in any manner departing from the scope of my said invention or inventions herein 60 first disclosed and claimed.

And inasmuch as several individual portions of the mechanism herein claimed individually, are applicable to be used in automatic feeding and delivering machines other 65 than electric heating machines, I do not intend to limit myself in the broader claims hereof, strictly to use thereof in such type of machines, as it is evident that my improved slotted circular carrier-plates with 70 axially and peripherally holding and delivering slots, especially when coupled with my combined stock-guard and ejector member, as well as my adjustable slot-plates for varying the widths of each individual carrier-slot are each and all generally and combined adaptable for use in any and all machines, electric-heating or non-electric-heating, where automatic feed and delivery is 75 desirable; and in the broad claims hereof 80 relating to such mechanisms immediately above enumerated, I intend to claim such mechanisms both individually and collectively, when applied to and used in automatically feeding and delivering machines 85 for every name and nature, wherever such mechanisms, singly or collectively in combination, are capable of use therein.

I claim—

1. In a device of the class described, a 100 moving carrier-member having a plurality of rivet carrying slots open ended at their rear ends relative to the direction of movement of the carrier-member for the ejection of the heated rivets; a guide-member located adjacent 105 to the moving carrier-member for preventing accidental removal of the rivets after insertion in the carrier-slots, during a step by step, intermittent movement thereof with a dwell for a predetermined time between each 110 two sequential movements, said guide member terminating to the rear of the ejecting position, and means for automatically ejecting the rivet or rivets from the carrier-member 115 upon the first partial movement of such carrier-member after the bringing of the said rivet or rivets sequentially to plastic working heat.

2. In a device of the class described, a moving carrier-member having a plurality 120 of rivet carrying slots open ended at their rear ends relative to the direction of movement of the carrier-member for the ejection of the heated rivets; a guide-member located adjacent to the moving carrier-member for preventing accidental removal of the rivets after insertion in the carrier-slots, during a step by step, intermittent movement thereof with a dwell for a predetermined time between each movement; said guide member 125 130

- terminating to the rear of the ejecting position, means for automatically ejecting the rivet or rivets from the carrier-member upon the first partial movement of such carrier-member after the bringing of the rivet or rivets sequentially to plastic working heat; and means or mechanism for simultaneously automatically bringing a fresh rivet or rivets to heating position.
- 5 10. 3. In a device of the character described, a moving carrier adapted to receive a plurality of articles to be sequentially heated; an electric heating current supply; a plurality of movable electrodes; a bridging electro-conductor member adapted to form a closed electric-circuit through a plurality of the articles to be heated when the movable electrodes by their movement bring such articles into contact with the bridging electro-conductive member, with a dwell sufficient to bring such articles to the proper working-heat; means or mechanism for automatically intermittently moving the carrier; and means for automatically ejecting the articles
- 15 20. 25. when they have been heated to the required working temperatures.
4. In a device of the character described, a moving carrier adapted to receive a plurality of articles to be sequentially heated; an electric heating current supply; a plurality of movable electrodes; a bridging electro-conductor member adapted to form a closed electric-circuit through a plurality of the articles to be heated when the movable electrodes by their movement bring such articles into contact with the bridging electro-conductive member, with a dwell sufficient to bring such articles to the proper working-heat; the current passing thru one movable electrode thru one article to the bridge-member, thru which it passes in series thru another article to a second movable electrode, and thence to the minus (-) pole of the electric heating current supply; means or mechanism for automatically intermittently moving the carrier; and means for automatically ejecting the articles when they have been heated to the required working temperatures.
- 30 35. 5. A device of the class described, comprising a moving carrier having a plurality of stock-carrying slots open at one end to deliver the stock when heated to plasticity; and adjustable means for varying the width of each of such slots for use with stock of different sizes or diameters.
- 40 45. 6. A device of the class described, comprising a substantially circular intermittently rotating carrier-plate having a spider open-work portion surrounding the hub; a plurality of curved stock-carrying slots open at the peripheral end; a plurality of like slots opening into the orifices of the spider; and an adjustable member for individually varying the width of each adjacent pair of
- 50 55. inner and outer slots, in such manner as to adapt the same to holding therein stock of different sizes or diameters.
- 60 65. 7. A device of the class described, comprising a substantially circular intermittently rotating carrier-plate having a spider open-work portion surrounding the hub; a plurality of curved stock carrying-slots open at the peripheral end; a plurality of like slots opening into the orifices of the spider; and an adjustable-member for varying the width of each adjacent pair of inner and outer slots, concaved on the inner side to the contour of the curved outer wall-face of the inner spider-slots, and on the outer side convexed to the contour of the inner wall-face of the outer peripheral slots; and means for securing such adjustable member or members in any required position.
- 70 75. 8. A device of the class described, comprising a substantially circular intermittently rotating carrier-plate having a spider open-work portion surrounding the hub; a plurality of curved stock carrying slots open at the peripheral end; a plurality of like slots opening into the orifices of the spider, and an adjustable-member or members for varying the width of each adjacent pair of inner and outer slots, concaved on the inner side to the contour of the curved outer wall-face of the inner spider-slots; and on the outer side convexed to the contour of the inner wall-face of the outer peripheral slots; and means for securing such adjustable member or members in any required position.
- 80 85. 9. A device of the class described, comprising a substantially circular intermittently rotating carrier-plate having a spider open-work portion surrounding the hub; a plurality of curved stock carrying slots open at the peripheral end; a plurality of like slots opening into the orifices of the spider, and an adjustable-member or members for varying the width of each adjacent pair of inner and outer slots, concaved on the inner side to the contour of the curved outer wall-face of the inner spider-slots; and on the outer side convexed to the contour of the inner wall-face of the outer peripheral slots; and means for securing such adjustable member or members in any required position, in such manner as to adapt the same to holding therein stocks of different sizes or diameters.
- 90 95. 10. A device of the class described, comprising a substantially circular intermittently rotating carrier-plate having a spider open-work portion surrounding the hub; a plurality of curved stock carrying slots open at the peripheral end; a plurality of like slots opening into the orifices of the spider; and an adjustable-member for varying the width of each adjacent pair of inner and outer slots, concaved on the inner side to the contour of the curved outer wall-face of the inner spider-slots, and on the outer side convexed to the contour of the inner wall-face of the outer peripheral slots; and means for securing such adjustable member or members in any required position, in such manner as to adapt the same to holding therein stocks of different sizes or diameters.
- 100 105. 11. A device of the class described, comprising a substantially circular intermittently rotating carrier-plate having a spider open-work portion surrounding the hub; a plurality of curved stock carrying slots open at the peripheral end; a plurality of like slots opening into the orifices of the spider; and an adjustable-member for varying the width of each adjacent pair of inner and outer slots, concaved on the inner side to the contour of the curved outer wall-face of the inner spider-slots, and on the outer side convexed to the contour of the inner wall-face of the outer peripheral slots; and means for securing such adjustable member or members in any required position, in such manner as to adapt the same to holding therein stocks of different sizes or diameters.
- 110 115. 12. A device of the class described, comprising a substantially circular intermittently rotating carrier-plate having a spider open-work portion surrounding the hub; a plurality of curved stock carrying slots open at the peripheral end; a plurality of like slots opening into the orifices of the spider; and an adjustable-member for varying the width of each adjacent pair of inner and outer slots, concaved on the inner side to the contour of the curved outer wall-face of the inner spider-slots, and on the outer side convexed to the contour of the inner wall-face of the outer peripheral slots; and means for securing such adjustable member or members in any required position, in such manner as to adapt the same to holding therein stocks of different sizes or diameters.
- 120 125. 13. A device of the class described, comprising a substantially circular intermittently rotating carrier-plate having a spider open-work portion surrounding the hub; a plurality of curved stock carrying-slots open at the peripheral end; a plurality of like slots opening into the orifices of the spider; and an adjustable member for individually varying the width of each adjacent pair of
- 130

- and an adjustable-member for varying the width of each adjacent pair of inner and outer slots, (split into two parts along the line of its curved path of adjustment, 5 whereby the inner slot may be made of one width, and the outer of another) concaved on the inner side to the contour of the curved outer wall-faces of the inner spider-slots; and on the outer side convexed to the contour 10 of the inner wall-face of the outer peripheral slots; and means for securing such adjustable member in any required position in such manner as to adapt the slots to hold therein stocks of different diameters, such 15 adjustable members comprising a curved slot or slots, and securing means located in such slot, and screwing into the carrier-plate.
11. A device of the class described, comprising a plurality of substantially circular stock carrying-plates having stock-carrying slots open toward the axis, and other like stock-carrying and delivering slots opening at the periphery; and mechanism for automatically intermittently rotating such 20 stock-carrying plates by a step by step movement, with a predetermined timed working dwell between movements.
12. A device of the class described, comprising a plurality of substantially circular stock carrying-plates having stock-carrying slots open toward the axis, and other like stock-carrying and delivering slots opening at the periphery; and mechanism for automatically intermittently rotating such 25 carrying-plates by a step by step movement with a predetermined timed working dwell between movements; in such manner that the adjacent abutting edges of each pair of wheels move toward the front of the machine, whereby the empty stock-carrying slots to be supplied with fresh stock are found at or adjacent to the extreme front of the machine.
13. A device of the class described, comprising a plurality of substantially circular stock-carrying plates having stock-carrying and delivering slots open toward the axis, and other like stock-carrying and delivering slots opening at the periphery; and mechanism for automatically intermittently rotating such stock-carrying plates by a step by step movement with a predetermined timed working dwell between movements; in such manner that the adjacent abutting 30 edges of each pair of wheel-like carrier-plates move toward the front of the machine, whereby the empty stock-carrying slots to be supplied with fresh stock are found at or adjacent to the extreme front of the machine; the two wheels rotating alternately so that when one is in the heating dwell, the other is in rotative movement.
14. A device of the class described, comprising a plurality of substantially circular stock-carrying plates having stock-carrying 35 and delivering slots open toward the axis; and other like stock-carrying and delivering slots, opening at the periphery; the open ends of the slots being at the rear relative to the direction of movement of said plates, and mechanism for automatically intermittently rotating such stock-carrying plates by a step by step movement with a predetermined timed working dwell between movements.
15. In a rivet heater, a clamp comprising upper and lower rivet engaging electrodes, and a disk rotatable upon a vertical axis, said disk being positioned with a peripheral portion between said electrodes and having a plurality of rivet receiving notches in the periphery thereof.
16. In a rivet heater, a clamp comprising rivet engaging electrodes, a rotatable disk having a peripheral portion positioned between said electrodes and having means adjacent its periphery supporting a plurality of rivets, and means for simultaneously opening said clamp and imparting a rotative movement to said disk.
17. In a rivet heater, a clamp comprising a stationary and a movable electrode, a rotatably mounted disk having a peripheral portion positioned between said electrodes and having means adjacent its periphery for supporting a series of rivets, means for opening the clamp and means operably connected to said clamp for imparting a step by step motion to said disk.
18. A rivet heater comprising a pair of clamping electrodes, one of said electrodes being movable toward and from the other, a spring for pressing said movable electrode toward the opposing electrode, a lever connected to said movable electrode for moving said electrode away from the opposing electrode, and a rivet feeding mechanism operably connected to said lever to feed a rivet into position between the electrodes upon operation of said lever.
19. In a rivet heater, a clamp comprising a pair of opposed electrodes, means for operating said clamp, a magazine for holding a plurality of rivets and means operably connected to said clamp operating means for transferring rivets from said magazine to a position between said electrodes.
20. In a rivet heater, a clamp comprising a pair of opposed electrodes, a rivet magazine, and means for opening said clamp and for transferring rivets from the magazine to the clamp.
21. In a rivet heater, a clamp comprising a pair of clamping electrodes, one of said electrodes being movable toward and from the other, a support for supporting a rivet by its head, means for actuating said support to feed a rivet into position between said electrodes, and means for moving said movable electrode into engagement with the

lower end of the rivet to press the head of the rivet into engagement with the other electrode.

22. In a rivet heater, a clamp comprising a pair of clamping electrodes, one of said electrodes being movable toward and from the other, a support for a rivet with its ends exposed, means for actuating said support to feed a rivet into position between said electrodes, and means for moving said movable electrode into engagement with one end of the rivet and to actuate said rivet to press the other end of said rivet into engagement with the other electrode.

23. In a rivet heater, a magazine for rivets, means for actuating said magazine in one direction to position the rivet to be heated in axial alinement with its heating position, and means for clamping the rivet in its heating position.

24. In a rivet heater, a magazine for rivets, a pair of opposed electrodes, means for actuating said magazine in one direction to position the rivet to be heated in axial alinement with its heating position in contact with said electrodes, and means for clamping the rivet in engagement with said electrodes in its heating position.

25. In a rivet heater having a heating position for a rivet, a magazine for rivets, means for actuating said magazine in one direction to position the rivet to be heated in alinement with its heating position preparatory to being positioned in its heating position, and a movable member for anchoring the member to be heated in its heating position.

26. In a rivet heater having a heating position for a rivet to be heated, a magazine for rivets, a pair of opposed electrodes, and means for actuating said magazine in one direction to position the rivet to be heated in alinement with its heating position, the magazine constituting a guide to guide the rivet during its movement into heating position.

27. In a rivet heater having a heating position for a rivet to be heated, a magazine for rivets, a pair of opposed electrodes, means for actuating said magazine in one direction to position the rivet to be heated in alinement with its heating position, the magazine constituting a guide to guide the rivet during its movement into heating position, and a movable member for clamping the member to be heated in the heating position.

28. In a rivet heater, a clamp comprising a pair of electrodes, one of said electrodes being movable toward and from the other, a support for a rivet, means for actuating said support to feed a rivet into alinement with said electrodes, and a spring operatively con-

nected to actuate said movable electrode to clamp the alined rivet between said pair of electrodes.

29. In a rivet heater, a clamp comprising a pair of electrodes, one of said electrodes being movable toward and from the other, a support for a rivet, a spring for moving the movable electrode into heating position, a lever operatively connected to said movable electrode, and means for actuating said support to feed a rivet into alinement with said electrodes and for actuating said lever to withdraw said movable electrode out of heating position.

30. In a rivet heater, a clamp comprising a pair of electrodes, one of said electrodes being movable toward and from the other, a support for a rivet with its ends exposed, a spring operatively connected to said movable electrode, a lever operatively connected to said movable electrode, and means for actuating said support to feed a rivet into alinement with said electrodes and for subsequently actuating said lever to withdraw said movable electrode out of heating position, the spring being operable to actuate the movable electrode into engagement with one end of the rivet to be heated and moving the rivet into its heating position in engagement with the other electrode.

31. In a rivet heater, a rotatable rivet holding means for supporting the rivets with their ends exposed, a pair of opposed electrodes, means for advancing said rivet holding means at intervals successively to present the exposed ends of the rivets into contact with the electrodes for heating, and means for clamping the exposed ends of the rivets into engagement with said electrodes to be heated.

32. In an electric heater, the combination with a rotatable work holding means for supporting the work to be electrically heated, of a pair of opposed electrodes, means for rotating said work holding means at intervals successively to present the work to be heated to the electrodes and means for clamping exposed portions of such work in direct engagement with said electrodes to be heated.

33. In a rivet heater comprising a pair of clamping electrodes, a rivet feeding mechanism, means for operating said feeding mechanism at intervals successively to present the rivets to the electrodes for heating, means for normally causing said electrodes to approach one another and clampingly engage the exposed ends of a rivet, and means for intermittently withdrawing said electrodes from one another to accommodate the discharge of a heated rivet and the reception of a succeeding rivet.

GEORGE A. E. JONES.
